CLAIM

The ornamental design for a computer keyboard, as shown and described.

DESCRIPTION

FIG. 1 is a top perspective view of a computer keyboard showing my new design;

FIG. 2 is a left side elevational view thereof;

FIG. 3 is a right side elevational view thereof;

FIG. 4 is a front side elevational view thereof;

FIG. 5 is a rear side elevational view thereof;

FIG. 6 is a top plan view thereof;

FIG. 7 is another top perspective view thereof;

FIG. 8 is a left side perspective view thereof;

FIG. 9 is a right side perspective view thereof; and,

FIG. 10 is another top perspective view.

The bottom of the computer keyboard is flat and unornamented.

The portions and surfaces shown in broken lines underneath the keys form no part of the claimed design.
